MICHAEL J. CAWLEY, OF NEW YORK, N. Y., ASSIGNOR TO MILDRED M. DANIELS, OF NEW YORK, N. Y.

BURGLAR-ALARM DEVICE.

Application filed August 19, 1927. Serial No. 213,937.

This invention relates to switch devices and particularly to devices of this class for use in connection with alarm circuits for protecting doors of residences, banks, bank vaults, as well as for controlling any member governing the admission to a room or compartment of any kind or class, as well as to a switch device which may operate to control a member, device or mechanism or apparatus of any kind or class, such for example as the devices or mechanisms controlling the operation of a motor vehicle; and the object of the invention is to provide a switch device which is adapted to be mounted in connection with the door or other member to be controlled and provided externally of said door with a dial by means of which the proper setting of the switch is facilitated; a further object being to provide a contact disk constituting part of a notched disk adjustably supported in connection with the door to permit of its setting into different positions and a spring contact arm movably disposed over the surface of the contact disk to control the alarm circuit, said contact disk having a non-conducting surface at a predetermined point thereon with which said spring contact is adapted to register; a further object being to provide a device of the class specified which by virtue of the structure employed will take up comparatively little room on the door or other member in connection with which the same is mounted, and which will be simple and positive in operation; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a diagrammatic view illustrating my improved switch device mounted in an alarm circuit.

Fig. 2 is a sectional detail view of the switch device supported in connection with a door or other member.

Fig. 3 is a section on the line 3—3 of Fig. 2.

Fig. 4 is a section on the line 4—4 of Fig. 2.

Fig. 5 is a section on the line 5—5 of Fig. 2.

Fig. 6 is a perspective detail view of the switch arm which I employ; and

Fig. 7 is a face view of the dial control.

In Fig. 1 of the drawing, I have shown for the purpose of illustrating one method of carrying my invention into effect, an alarm circuit wherein 5 represents batteries or other source of electric supply, one wire 6 from said source extending to one side of terminal 7 of a circuit connecting a breaking device 8 which is controlled by the opening and closing of the door 9, while the other wire 10 from said source extends to an electromagnet 11 and from said magnet to a bell or signal device 12, to the wire 13 and to one contact 14 of my improved switch device 15 to the wire 16. Another wire 17 from the contact 18 of the switch device 15 extends through a manually controlled switch 19 to the other contact 20 of the circuit making and breaking device 8. The wire 21 is coupled with the bell or signal device 12 and with the wire 10, and another wire 22 is coupled with said signal device and with the wire 6, the circuit through the last named wire being controlled by the armature 23 actuated by the electromagnet 11, the latter construction serving to maintain the circuit closed to the signal device 12 to constantly sound the alarm until such circuit is broken, when the circuit is once put in operation by the device 8 which is controlled through the switch device 15.

The contact 14 in the construction shown consists of a cup-shaped disk having a back wall 14^a and a peripheral flange 14^b extending at right angles to the back wall to form the casing proper of the switch device which is secured to the inner face of the door 9 as seen at 14^c. Riveted or otherwise secured to the back wall 14^a is a disk 24 of insulating material having two outwardly projecting hook-shaped fingers 25 adapted to engage notches 18^a in the disk 18 to secure the disk 18 in connection with the contact disk 14 or the back wall 14^a thereof. The disk 18 is insulated therefrom by an insulating disk or washer 26.

It will be understood that the parts 14, 18 and 24 will be assembled as a unit or to form a unit structure. At 27, I have shown the operating shaft which is passed through an aperture in the door 9, the shaft being provided at the outer side of the door with an op-

erating knob 28 having an indicating finger 29 which cooperates with the dial plate 30 secured to the outer face of the door 9. The inner end of the shaft 27 is flattened on two sides as seen at 27^a and threaded on its other side as seen at 27^b. Mounted on the inner end of the shaft is an adjustment wheel 31, the periphery of which is provided with a plurality of notches 32 in connection with which a spring pawl 33 operates. The latter is secured to the flange 14^b of the contact 14, and the wheel 31 is adapted to be rotated to bring the same into different positions of the adjustment with reference to the indicating finger 29 of the knob 28 for the purpose of bringing a non-conducting surface 34 of a contact disk 35 in predetermined position with reference to the numerals of the dial 30. The disk 35 is arranged on one side face of the wheel 31 and is secured thereto by three fingers 36 passed through apertures in the wheel 31 which are bent upon the opposite face of the disk, forming three contact surfaces which are adapted to engage the contact disk 18, thus completing the circuit from the wire 17 to the disk 35.

The shaft 27 contacts with the contact 14 as seen at 37 so as to place the shaft 27 in circuit with the wire 16. Secured to the shaft 27 inwardly of the wheel 31 is a spring contact finger 38 having an aperture 39 to fit upon the flat sides 27^a of the shaft 27 to key the finger 38 therewith, and the free end of said finger is bent into hook fashion as seen at 40 and is adapted to tensionally engage the disk 35 and move freely thereover as well as over the non-conducting surface 34 of the disk 35. The finger 38 is held in position on the shaft 27 and the wheel 31 is also held in its position by a nut 41 in threaded engagement with the shaft 27, between which nut and the finger 38 is placed a spring washer 42.

I also employ a cup-shaped cover 43 which is mounted upon the flange portion 14^b of the contact 14 and retained against displacement therefrom by engagement with a number of pins 44 on said contact operating in bayonet or other slots in the cover 43.

With my improved construction, it will be understood that the fingers of the contact disk 35 are held in firm engagement with the contact disk 18 and the spring contact finger 38 tensionally engages the disk 35 at all times. In the use of the device, the knob 28 is rotated to bring the finger 38 into alignment with the non-conducting surface 34 by breaking the circuit through the wires 16 and 18 to permit of the opening of the door without sounding the alarms of the circuit. The operator is guided in this operation by the movement of the finger 29 into registering position with one of the indicating marks of the dial 30. Whenever desired, the wheel 31 may be adjusted to move the non-conducting surface 34 into different positions with reference to the

numerals of the dial 30 to change the combination. This result is accomplished by removing the cap 43, grasping the finger 38 in one hand and rotating the wheel 31 by the other hand. The notches 32 serve to accurately place the non-conducting surface 34 with reference to the markings of the dial. In this operation, the nut 41 may be loosened if desired, but this is not absolutely necessary.

75

It will also be understood that while I have shown certain details of construction for carrying my invention into effect, that I am not necessarily limited to these details, and various changes in and modifications of the construction herein shown and described may be made within the scope of the appended claims, without departing from the spirit of my invention or sacrificing its advantages.

80

It will be apparent that while I have illustrated and described my invention as applied to a door, that the same may be used in connection with and adapted to control devices, mechanisms or apparatus of any kind or class, for example, a switch device may be employed to control, by virtue of its electric circuit, in the operation of control devices or mechanisms of a motor vehicle to prevent the theft of such vehicles, and many other uses which will present themselves to those skilled in the art.

85

Having fully described my invention, what I claim as new and desire to secure by Letters Patent, is:-

90

1. A switch device of the class described comprising a manually actuated member, means for indicating the several positions of said member, an electric spring contact finger actuated by said member and movable over a contact surface supported in the path of movement of said contact, an insulated surface interposed in the path of said contact to break the circuit thereto, a notch adjustment wheel supporting said contact surface and a stationary contact disk, and means for placing the contact surface of said wheel in direct contact with said stationary contact disk.

100

2. A switch device of the class described comprising a manually actuated member, means for indicating the several positions of said member, an electric spring contact finger actuated by said member and movable over a contact surface supported in the path of movement of said contact, an insulated surface interposed in the path of said contact to break the circuit thereto, a notch adjustment wheel supporting said contact surface and a stationary contact disk, means for placing the contact surface of said wheel in direct contact with said stationary contact disk, and means for insulating said stationary contact disk from said manually actuated member.

115

3. A switch device of the class described

120

125

130

comprising a cup-shaped casing, a shaft mounted in and in circuit with said casing, a stationary contact disk supported in connection with said casing and insulated from said shaft and said casing, a notched wheel mounted on said shaft and adapted to be keyed in different positions of adjustment in said casing, said wheel having a contact surface, means for placing said contact surface in electric contact with said stationary contact disk, a spring contact arm on said shaft and rotatable therewith, said arm being movable over and tensionally engaging the contact surface of said wheel, and a non-conducting surface in the path of said spring contact arm.

4. A switch device of the class described comprising a cup-shaped casing, a shaft mounted in and in circuit with said casing, a stationary contact disk supported in connection with said casing and insulated from said shaft and said casing, a notched wheel mounted on said shaft and adapted to be keyed in different positions of adjustment in said casing, said wheel having a contact surface, means for placing said contact surface in electric contact with said stationary contact disk, a spring contact arm on said shaft and rotatable therewith, said arm being movable over and tensionally engaging the contact surface of said wheel and a non-conducting surface in the path of said spring contact arm, and a nut in threaded engagement with said shaft for retaining said spring contact arm and said wheel against displacement therefrom.

5. A switch device of the class described comprising a cup-shaped casing, a shaft mounted in and in circuit with said casing, a stationary contact disk supported in connection with said casing and insulated from said shaft and said casing, a notched wheel mounted on said shaft and adapted to be keyed in different positions of adjustment in said casing, said wheel having a contact surface, means for placing said contact surface in electric contact with said stationary contact disk, a spring contact arm on said shaft and rotatable therewith, said arm being movable over and tensionally engaging the contact surface of said wheel and a non-conducting surface in the path of said spring contact arm, and said wheel against displacement therefrom, and a cap detachably coupled with said casing and enclosing the remainder of said switch device.

6. A switch device of the class described comprising a cup-shaped casing, a shaft mounted in and in circuit with said casing, a stationary contact disk supported in connection with said casing and insulated from said shaft and said casing, a notched wheel mounted on said shaft and adapted to be keyed in

different positions of adjustment in said casing, said wheel having a contact surface, means for placing said contact surface in electric contact with said stationary contact disk, a spring contact arm on said shaft and rotatable therewith, said arm being movable over and tensionally engaging the contact surface of said wheel and a non-conducting surface in the path of said spring contact arm, a nut in threaded engagement with said shaft for retaining said spring contact arm and said wheel against displacement therefrom, a cap detachably coupled with said casing and enclosing the remainder of said switch device, and an indicating knob on the outer end of said shaft and adapted to operate with a dial secured to a support through which said shaft passes.

7. A switch device comprising a casing with which one circuit wire is adapted to be coupled, a stationary contact disk secured to said casing and insulated therefrom and with which the other wire of said circuit is coupled, and a switch member for opening and closing the circuit through said wires comprising a shaft passing through said casing and in contact therewith and insulated from said stationary contact disk, an adjustable contact disk having a non-conducting surface in circuit with said stationary contact disk and through which said shaft passes and is insulated therefrom, and a switch arm secured to said shaft and rotatable over the adjustable contact disk and said non-conducting surface to control the circuit through said wires.

8. A switch device comprising a casing with which one circuit wire is adapted to be coupled, a stationary contact disk secured to said casing and insulated therefrom and with which the other wire of said circuit is coupled, and a switch member for opening and closing the circuit through said wires comprising a shaft passing through said casing and in contact therewith and insulated from said stationary contact disk, an adjustable contact disk having a non-conducting surface in circuit with said stationary contact disk and through which said shaft passes and is insulated therefrom, a switch arm secured to said shaft and rotatable over the adjustable contact disk and said non-conducting surface to control the circuit through said wires, and means for keying the adjustable contact disk in different positions of adjustment with reference to the casing.

9. A switch device comprising a casing with which one circuit wire is adapted to be coupled, a stationary contact disk secured to said casing and insulated therefrom and with which the other wire of said circuit is coupled, and a switch member for opening and closing the circuit through said wires comprising a shaft passing through said casing and in contact therewith and insulated

from said stationary contact disk, an adjustable contact disk having a non-conducting surface in circuit with said stationary contact disk and through which said shaft passes and is insulated therefrom, a switch arm secured to said shaft and rotatable over the adjustable contact disk and said non-conducting surface to control the circuit through said wires, means for keying the adjustable contact disk in different positions of adjustment with reference to the casing, and means for supporting the contact arm and said adjustable contact disk on said shaft.

10. A switch device comprising a casing with which one circuit wire is adapted to be coupled, a stationary contact disk secured to said casing and insulated therefrom and with which the other wire of said circuit is coupled, and a switch member for opening and closing the circuit through said wires comprising a shaft passing through said casing and in contact therewith and insulated from said stationary contact disk, an adjustable contact disk having a non-conducting surface in circuit with said stationary contact disk and through which said shaft passes and is insulated therefrom, a switch arm secured to said shaft and rotatable over the adjustable contact disk and said non-conducting surface to control the circuit through said wires, means for keying the adjustable contact disk in different positions of adjustment with reference to the casing, means for supporting the contact arm and said adjustable contact disk on said shaft, and means at the outer end of said shaft for indicating the several positions of rotatable adjustment thereof.

11. In a switch device of the class described, an adjustable wheel, the periphery of which is provided with a plurality of notches, a spring pawl for engaging the notches of said wheel to retain the same in different positions of adjustment, a contact disk on one face of said wheel and having a radially arranged

non-conducting surface at one point of its periphery, said contact disk having prongs passed through said wheel to expose said disk at the opposite face of the wheel for engagement with another contact.

50

12. In a switch device of the class described, an adjustable wheel, the periphery of which is provided with a plurality of notches, a spring pawl for engaging the notches of said wheel to retain the same in different positions of adjustment, a contact disk on one face of said wheel and having a radially arranged non-conducting surface at one point of its periphery, said contact disk having prongs passed through said wheel to expose said disk at the opposite face of the wheel for engagement with another contact, and means for rotatably supporting a spring contact arm with reference to said contact disk to tensionally engage the same and said non-conducting surface.

55

60

65

13. In a switch device of the class described, an adjustable wheel, the periphery of which is provided with a plurality of notches, a spring pawl for engaging the notches of said wheel to retain the same in different positions of adjustment, a contact disk on one face of said wheel and having a radially arranged non-conducting surface at one point of its periphery, said contact disk having prongs passed through said wheel to expose said disk at the opposite face of the wheel for engagement with another contact, and means for rotatably supporting a spring contact arm with reference to said contact disk to tensionally engage the same and said non-conducting surface, and a spring contact disk arranged to be engaged by the prongs of the first named contact disk and insulated from said spring contact arm.
